Philip S. McLean, ATTORNEY

UNITED STATES PATENT OFFICE.

SIGMUND SACHS, OF BRONX, NEW YORK

AUTOMATIC STAND FOR ELECTRIC IRONS.

Application filed September 6, 1924. Serial No. 736,238.

To all whom it may concern:

Be it known that I, SIGMUND SACHS, a citizen of the United States, and a resident of the Bronx, county of Bronx, and State of New York, have invented certain new and useful Improvements in Automatic Stands for Electric Irons, of which the following is a specification.

The objects of this invention are to provide a stand for supporting an electric iron which will combine with the functions of a support, a simple and practical means for automatically cutting off the heating current when the iron is not in use.

Various other objects of the invention and the novel features of construction, combinations and relations of parts by which the same are attained will appear in the course of the following specification.

In the drawing accompanying and forming part of the specification, the invention is illustrated in a practical commercial embodiment but as such illustration is primarily for purposes of disclosure, it should be understood that the structure may be varied and modified without departure from the broad spirit and scope of the invention as hereinafter defined and claimed.

Figure 1 is a broken perspective view illustrating the stand in use and showing the one continuous cord circuit from the supply outlet through the automatic switch in the stand to the iron.

Figure 2 is a top plan view of the stand partly broken away to illustrate the switch and connections.

Figures 3 and 4 are longitudinal and transverse sectional views of the stand, the latter as taken on line 4-4 of Figure 2.

Figures 5 and 6 are sectional and perspective detail views of the movable and stationary contact elements.

In the illustration 5 designates an iron of conventional design supplied with heating current by a flexible cord 6 provided with a plug 7 engageable with an ordinary outlet fixture 8.

As shown in the general view, the stand for the iron is interposed in the cord circuit, at a point to provide adequate length of cord for connection with the outlet fixture and to provide sufficient freedom for ordinary ironing purposes. Where, however, greater than ordinary freedom is required, the iron may be temporarily disconnected from the cord by simply detach-

ing the plug 9 which connects the cord with the terminals of the iron.

The stand is shown in the form of a base plate 10 of the general shape of the iron and having upstanding side flanges 11 for guiding the iron to a proper seat thereon. For ventilation purposes, this base plate is supported in raised position, by a foot or lug 12 at the front and by a dependent wall 13 at the rear. This latter is continued around to form a switch chamber which is closed at the bottom by a cap plate 14 removably secured in place by screws 15.

Within the switch chamber and shown as secured to the under side of the base plate at 16 is an insulating base 17 carrying at its under side a pair of spaced contacts 18, 19 arranged to be bridged by a contact 20 carried by a plunger 21 projecting up through a guide passage 22 in the insulating base and supporting base plate. This plunger is shown as positioned about midway or on the longitudinal center line of the stand adjacent the open rear of the same so as to be surely engaged by the iron even though it be carelessly placed or not fully entered over the stand.

The movable contact is shown in the form of an annular washer having lugs 23, 24 turned inward over a disc 24 of insulating material fixed on the plunger and the lower end of the plunger is shown as of reduced diameter and operating through a guide opening 25 in the cap plate.

Automatic engagement of the movable contact with the fixed contacts is effected in the illustration by a bowed spring 26 having a bearing on the cap plate and perforated in its intermediate portion to receive the reduced part of the plunger and engage with the shoulder 27 on the plunger.

In the rear wall of the switch chamber of the stand, insulating bushings 28, 29 are mounted for passage of the single length of conductor cord which is all that is necessary to use in this invention.

The stand can be wired by simply removing the cap plate 14 and threading the cord in through one insulating bushing and out through the other, leaving one of the conductors in the cord unbroken, in the form of a loop 30 within the switch chamber and cutting the other conductor, attaching one of the cut ends 31 to the binding screw 32 of stationary contact 18 and the cut end 33 to the binding screw 34 of the other sta-

tionary contact 19. The stand is tapped into this cord circuit at such an intermediate point as to leave plenty of cord to reach the outlet and an ample length of the cord for 5 use of the iron.

Because of its simplicity, few parts and manner in which it is braced by the convergent side flanges 11 and the front and rear supports, the stand can be made quite 10 light in weight. As a certain degree of solidity and stability is desirable in a support of this character, a relatively heavy stud 35 may be extended down from the central portion of the top plate to serve 15 both as a centrally located weight and as an extra foot for supporting the intermediate portion of the top plate. This foot prevents the top from sagging even when made of quite thin metal and prevents injury even if the iron be dropped heavily 20 onto the stand. By thus taking the shocks this foot serves to protect the switch structure. If additional solidity or fixity is desired, the stand may be secured fast upon 25 the ironing-board, table or other support by means of a suitable anchor screw extended up through the support into a screw seat 36 provided in the dependent weight and brace 35.

30 The switch plunger operates with a straight up and down motion and being guided at both top and bottom, shifts easily either with the weight of the iron to break the circuit or under impulse of the spring 35 to close the circuit.

35 The guide flanges 11 usually will stand higher than the tip of the switch plunger serving as guards to prevent an object from falling over the stand and breaking the circuit and also as raised supports upon 40 which the iron may be rested in case it should be found desirable to allow the iron to heat for a while, supported on the stand. The insulating washer which carries the 45 movable switch contact may be fixed on the plunger by a screw threaded connection, as indicated in Figure 5, and as this plunger is free to rotate it may turn, in the use of the stand, to present fresh contact surfaces 50 to the stationary switch elements.

55 All of the switch parts are wholly enclosed within the switch chamber in the bottom of the stand and so protected from mechanical injury, dust, moisture, etc., and the user of the device is fully protected 60 against any possible injury. The convergent guard flanges guide the iron squarely into position over the switch plunger without any special attention on the part of the user, the switch plunger being depressed by first engagement of the iron therewith and permitting the iron to slide freely to its 65 fully seated position on the stand.

What is claimed is:

65 1. A stand for electric irons having de-

pendent walls at the rear of the same forming a chamber and support, a removably secured cover plate closing said chamber, an insulating base on the under side of the stand within said chamber, terminals on said 70 insulating base, a spindle guided for vertical movement up through the top of the stand and down through the cover plate, a bridging contact for cooperation with the fixed switch contacts carried by and insulated with respect to said spindle, a bowed spring engaged over the lower portion of the spindle bearing at its ends against the 75 inside of the cover plate and operating to thrust the spindle upwardly to normally hold the plunger contact engaged with the stationary contacts.

2. A stand for electric irons having dependent supporting walls providing a downwardly open switch chamber, a plate removably secured to the stand and closing the bottom of said switch chamber, relatively movable switch contacts housed within said closed chamber and an actuating element for 80 said switch mechanism guided and yieldingly supported by said removable bottom cover plate.

3. A stand for electric irons, insulated switch contacts mounted in separated relation on the under side of said stand, a plunger guided for vertical sliding movement up through the top of the stand, a contact bridging element supported in insulated relation on said plunger, a guide for 95 the lower end of said plunger and spring means engaging said guide for yieldingly thrusting the plunger upwardly with the bridging contact engaged with the spaced contacts.

4. A stand for electric irons having a 105 switch chamber in the base of the same, a switch in said chamber comprising relatively fixed and movable contacts with an actuating element projecting up through the top of the stand for engagement by an iron 110 rested on the stand and a single circuit cord for extending from a circuit outlet through the switch chamber and out to the electric iron, one of the conductors of the cord being uninterrupted and extending through the 115 switch chamber in the form of a continuous loop and the other conductor of the cord being cut within the switch chamber and having the cut ends of the same engaged with the switch contacts, whereby the iron stand is connected with the outlet by one 120 length of the cord, the iron is connected with the stand by a continuation of the same cord and the circuit through the iron is controlled by placement of the iron on the 125 stand.

5. A stand for electric irons having a closed switch chamber in the base of the same, a switch in said chamber comprising fixed contacts and a movable contact having 130

- an actuating element projecting up through the top of the stand, insulating bushings in the rear wall of said switch chamber, a single circuit cord entered into the switch chamber through one of said bushings and extending out of the switch chamber through the other bushing, one of the conductors of said cord being left in the form of a continuous loop within the switch chamber and the other conductor of the cord being cut within the switch chamber and having the cut ends of the same engaged with the fixed switch contacts, a connector on one end of the cord outside the switch chamber for engagement with an electric outlet and a connector on the other end of the cord outside the switch chamber for engagement with an electric iron.
6. A stand for electric irons having a switch chamber in the base of the same, a switch located in said chamber and having an actuating part projecting up through the top of the same and stabilizing means carried by the stand for securing the stand in relatively fixed position upon an ironing board or the like so that the stand will not be pushed out of reach when an iron is slid over the same into engagement with the projecting switch actuating part.
7. A stand for electric irons having a switch in the base of the same provided with an actuating part projecting up through the top of the stand, guard flanges for guiding an iron into position over said actuating part and anchorage means for securing the stand in fixed relation upon an ironing-board or other support whereby said stand will not be pushed out of place in the act of sliding an iron over the same and into engagement with the projecting switch actuating part.
- 20 In witness whereof, I have hereunto set my hand this 3rd day of September, 1924.
- SIGMUND SACHS.
